UNITED STATES PATENT OFFICE.

JULIUS DREUSIKE, OF NEW YORK, N. Y.

IMPROVEMENT IN BOTTOMS FOR BEDS, &c.

Specification forming part of Letters Patent No. **143,970**, dated October 28, 1873; application filed August 8, 1873.

To all whom it may concern:

Be it known that I, JULIUS DREUSIKE, of the city, county, and State of New York, have invented certain Improvements in Spring-Bottoms, of which the following is a specification:

This invention relates to that class of bottoms where woven wire is used, and the object of my invention is to stiffen and strengthen the woven-wire bottom to prevent sagging, getting out of order, &c., and also to provide suitable additional springs to render the bed easy to lie upon after so strengthening said woven-wire bottom; and my invention consists, definitely, in the combination of an upper and under frame with spiral springs, as many as necessary, placed so that the spiral runs transversely with the side pieces of said frame, and the ends of spirals elongated for attachment to under side of side pieces of the upper frame, and upper side of side pieces of under frame, said springs in any number, as desired. It also consists in the combination, with said frame, of a woven-wire bottom, filling in the space between side and end pieces of upper frame, said woven-wire bottom formed of spirally-twisted wires, similar to what has been done heretofore, and also combined therewith, as a new feature thereof, wires running lengthwise the bed-frame and within the spirals of woven wire, and over or under (or both) the end cross-pieces of frame, and said woven-wire bottom having metal binding running transversely across each end, holding and binding together the ends of spiral wires, and also the lengthwise wires, and through which said lengthwise wires pass, returning without passing over end pieces of frame wherever desirable, so that the whole may be brought up taut, and the woven-wire bottom effectually prevented from sagging or bending downward too much, so as to get out of proper shape through uneven

pressure in use, making the bottom stiffer and less liable to get out of order, and a great deal stronger than those heretofore in use.

These bottoms are for beds, sofas, chairs, lounges, &c., and wherever a spring-bottom is useful.

Figure 1 is a side elevation. Fig. 2 is a lengthwise section. Fig. 3 is a horizontal view or plan. Fig. 4 is a transverse section through one side of frame, showing upper and under pieces, and one spring attached to each.

A represents side pieces of upper frame; B, end pieces of the same; C, side pieces of under frame; D, end pieces of the same. E are springs, combining the upper and under frame, one side only being shown, the other side having springs corresponding. The spiral twist of said springs runs transversely, and the ends of the same are fastened to under side of upper frame and to upper side of under frame. There may be as many of such springs as desired. I is the woven-wire bed-bottom. J represents the metal binding at each end. K are the lengthwise wires running through and within the spiral twist of woven wire. Said wires K, after passing through binding J, may return where desirable, and as shown in drawings, and at other points may be attached in any suitable manner to end pieces B of frame.

What I claim, and desire to secure by Letters Patent, is—

The combination of woven-wire bottom I, binding J, lengthwise wires K, upper frame A B, under frame C D, and springs E, constructed substantially in the manner and for the purpose described and set forth.

— JULIUS DREUSIKE.
